(57) **CLAIM**

The ornamental design for a play mat, as shown and described.

DESCRIPTION

FIG. 1 is a top, front, right side perspective view of a play mat, showing my design.

FIG. 2 is a bottom, rear, left side perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines shown in the drawings are included for the purpose of illustrating portions of the play mat that form no part of the claimed design.

1 Claim, 8 Drawing Sheets(56)
